UNITED STATES PATENT OFFICE.

GEORGE W. SHIEBLER, OF BROOKLYN, NEW YORK.

DESIGN FOR A SPOON.

SPECIFICATION forming part of Design No. 20,859, dated June 23, 1891.

Application filed May 25, 1891. Serial No. 394,068. Term of patent 3½ years.

To all whom it may concern:

Be it known that I, GEORGE W. SHIEBLER, a citizen of the United States, residing at Brooklyn, in the county of Kings and State 5 of New York, have invented a Design for a Spoon, of which the following is a specification.

The design of this spoon is represented in the accompanying drawings, in which—
10 Figure 1 represents the obverse side of the spoon, and Fig. 2 represents the reverse side of such spoon.

The leading feature of this design consists in the ornamental relief representation of a 15 stem with interlaced branches and leaves and a rounded end to the handle portion in connection with an ornamental bowl. The general outline of the handle is tapering, and the narrowest part is ornamented at *a* to repre-

sent a main stem, and from this are smaller 20 interlaced branches *b* and leaves, as represented, extending along the edges and surfaces of the handle. The plain portion *c* is on one side, and the end of the handle is 25 rounding at *e*. In the bowl are representations of boats and men and boxes, as shown in Fig. 1.

I claim—

1. The design of the obverse side of the spoon, substantially as represented. 30
2. The design of the reverse side of the spoon, substantially as represented.

Signed by me this 23d day of May, 1891.

GEO. W. SHIEBLER.
